E. SQUADRILLI.
LIQUID SOAP DISPENSER.

APPLICATION FILED JAN. 24, 1910.

UNITED STATES PATENT OFFICE.

EDUARDO SQUADRILLI, OF NEW YORK, N. Y., ASSIGNOR OF ONE-FOURTH TO ARTHUR ARBIB, OF NEW YORK, N. Y.

LIQUID-SOAP DISPENSER.

968,498.

Specification of Letters Patent. Patented Aug. 23, 1910.

Application filed January 24, 1910. Serial No. 539,754.

To all whom it may concern:

Be it known that I, EDUARDO SQUADRILLI, a citizen of the Kingdom of Italy, residing in New York, in the borough of Brooklyn, county of Kings, and State of New York, have invented certain new and useful Improvements in Liquid-Soap Dispensers, of which the following is a specification.

This invention relates to an improved 10 dispenser for liquid soap by which a predetermined quantity of liquid soap is discharged by a simple manual operation for use in the toilet-rooms of hotels, restaurants, public buildings etc., so that the use of a 15 cake of soap by different parties and the non-hygienic influence of the same is avoided.

In the accompanying drawings, Figure 1 represents a side-elevation of my improved 20 liquid soap dispenser, Fig. 2 is a vertical longitudinal section of the same, Fig. 3 is a detail side-view of the hollow sliding piston for producing the discharge of the liquid soap from the receptacle, and Fig. 4 is a 25 vertical transverse section on line 4, 4, Fig. 3.

Similar letters of reference indicate corresponding parts throughout the several figures.

Referring to the drawings, *a* represents 30 a receptacle for liquid soap, which may be made of glass or other suitable material and of spherical, oval or other shape. The receptacle *a* is provided at its upper end with a removable screw-cap *a*¹ having a 35 central opening *a*². When the receptacle *a* is to be filled with liquid soap, the screw-cap *a*¹ is removed and then replaced after filling the same.

b represents a tubular bracket-arm which 40 is provided with an attaching plate *b*¹ having holes for suitable screws *b*² for securing the device to a wall or other suitable support. The tubular bracket *b* is provided with two tubular portions *d*, *d*¹ which extend in line with each other at right-angles 45 to the horizontal portion of the bracket, the upper tube *d* being provided with an interiorly-threaded seat *d*² for receiving the exteriorly-threaded lower end or neck *a*³ of the receptacle *a*. The tubular bracket *b*¹ is provided at diametrically opposite points 50 with ports or openings *o*¹ and *o*³, the former affording communication between the interior of said tubular bracket and the supply pipe *d* and the latter affording communication be-

tween said tubular bracket and the discharge pipe *d*¹. A gasket *d*³ of rubber or other suitable material is interposed between the lower end of the neck of the receptacle and the seat of the enlarged end of the tubular arm *d*¹. The lower tube *d*¹ of the bracket *b* forms a discharge-spout for the tubular front-portion of the bracket, which tubular portion is separated by a transverse partition *b*³ from the main-portion of the bracket, as 65 shown in Fig. 2.

In the tubular portion of the bracket *b* is arranged a tubular piston *f* which is open at the inner end, the stem *f*¹ of which is guided in the opening of a screw-cap *b*⁴, 70 which is screwed over the exteriorly-threaded end of the tubular front-portion of the bracket-arm *b*. An elastic packing ring is interposed between the head of the piston *f* and the screw-cap *b*⁴ so as to prevent any 75 escape of liquid soap along the stem of the piston. The stem *f*¹ is provided at its outer end with a push-button *f*² which is attached on the end of the stem *f*¹, as shown clearly in Fig. 2.

Between the partition *b*³ of the bracket-arm *b* and the head of the tubular piston is interposed a helical spring *f*³ which is located in the tubular portion of the piston *f*. The tubular piston *f* is provided along its 85 side with a longitudinal groove *f*⁴ which is engaged by a fixed screw *f*⁵, that passes through a small opening in the tubular portion of the bracket *b* and engages the longitudinal groove *f*⁴ of the piston so as to 90 prevent the turning of the piston on its axis during its inward or outward motion. The tubular piston *f* is provided at its upper part with an inlet port or opening *o*, which registers in the normal position of the piston 95 with the corresponding opening *o*¹ at the lower end of the upper tube *d*, so that the liquid soap can pass from the receptacle *a* through the upper tube *d* and the openings *o*¹ *o* into the interior of the piston and into 100 the tubular front-portion of the bracket *b* filling this space entirely with liquid soap. The piston *f* is further provided at its lower part, but at a distance in front of the opening *o* about equal to the length of said opening with a second opening *o*², which registers with the upper end of the lower tube or discharge-spout *d*¹ when the piston is forced inwardly. During the inward motion of 105 the piston pressure is exerted on the liquid 110

in the tubular portion of the bracket, which as long as the opening o of the piston communicates with the opening o^1 at the lower end of the supply-tube d permits the liquid 5 to be pressed upwardly through these openings, but as soon as the opening o passes the opening o^1 and is out of register with the same, the opening o^2 in the lower part of the piston and the opening o^3 of the discharge-tube are placed in register and a certain quantity of liquid ejected through the spout d^1 . On releasing the knob of the piston-rod, the spring f^3 returns the piston into its former normal position so that the 15 liquid can be again supplied through the openings o , o^1 to the interior of the piston and the cylindrical front-portion of the tube d . The quantity of liquid discharged at each inward motion of the piston is approximately the same.

The piston is preferably operated by the right hand and the liquid soap delivered onto the left hand, which is held below the discharge-spout and then used for cleaning 25 the hands.

As soon as the pressure on the push-button f^2 is relaxed, the helical spring f^3 returns the piston into normal position, so that the openings o and o^1 are again placed 30 in register. As the liquid soap in the receptacle is under atmospheric pressure, a new supply of liquid soap is supplied to the interior space of the piston so as to replace the quantity of liquid soap discharged previously by the inward motion of the piston. The operation of pushing the piston inwardly and discharging the predetermined 35 quantity of liquid soap can then be repeated until the entire quantity of liquid soap in the 40 receptacle is used up.

The liquid soap dispenser can be used for discharging other liquid materials, such as toilet cream, medicated or perfumed oils and disinfecting or any other substances, so 45 that the dispenser can be used for ladies' toilet rooms and in connection with wash-basins in public or private places.

In the use of this liquid soap dispenser a uniform quantity of liquid soap or other 50 substance is positively discharged by the pressure of the piston on the liquid, so that

absolutely the same quantity is discharged at every inward pressure of the same, while the same quantity is replaced by gravity from the receptacle into the space at the interior of the piston. This renders the function of the dispenser uniform and reliable, especially when the liquid thickens after some time and assumes a certain consistency, the piston will still force out the quantity required.

The apparatus does not leak and the soap or other liquid does not deteriorate as there is but little access of air to the same.

This dispenser presents a symmetrical appearance with its supply and discharge pipes disposed at diametrically opposite points, and its hollow piston, operative in connection with the so disposed pipes, causes the soap contained in the liquid receptacle supported by the bracket to be forcibly discharged at a convenient point.

Having thus described my invention, what I claim as new and desire to secure by Letters Patent is:

A dispensing apparatus for liquid soap or similar substances, comprising a tubular bracket provided at one end with attaching means and at the other end with a closing device and intermediately with lateral supply and discharge pipes disposed opposite each other, a liquid receptacle secured to said supply pipe, a reciprocating tubular piston disposed in said tubular bracket and provided with an inlet port on its upper side adapted to register when the piston is in outward position with said supply pipe, and with an outlet port on its under side forward of said inlet port a distance about equal to the length of said port and adapted to register when the piston is pressed inward with said discharge pipe, a spring for normally holding said hollow piston in outward position, and means for preventing the rotation of said piston.

In testimony, that I claim the foregoing as my invention, I have signed my name in presence of two subscribing witnesses.

EDUARDO SQUADRILLI.
